UNITED STATES PATENT OFFICE.

PETER WARD, OF RYE, NEW YORK.

FOOT-REST.

SPECIFICATION forming part of Letters Patent No. 480,797, dated August 16, 1892.

Application filed September 15, 1891. Serial No. 405,801. (No model.)

To all whom it may concern:

Be it known that I, PETER WARD, of Rye, Westchester county, New York, have invented an Improved Foot-Rest for Chairs, of which 5 the following is a specification.

This invention relates to an adjustable foot-rest of novel construction and designed to be used for office-stools, babies' chairs, and similar articles of furniture.

10 It consists in the various features of improvement more fully pointed out in the claim.

In the accompanying drawings, Figures 1 and 2 are elevations of a stool provided with 15 my improved foot-rest and taken at right angles to each other. Fig. 3 is an enlarged section on line x x , Fig. 2; Fig. 4, an end view of the foot-board, and Fig. 5 a vertical section through the same. Fig. 6 is a side 20 view, on an enlarged scale, of the rack with the foot-board tilted.

The letters a a represent the legs of a chair, stool, or similar article of furniture. To two 25 of these legs there are secured upright racks b , placed parallel to each other and provided with the inwardly-bent ends b' , so that the racks stand off from the chair-legs.

c is the foot-board, extending across the racks, Fig. 1. This foot-board is provided 30 with a beveled inner edge c' , that is reinforced by a base-plate c^2 , sunk into the foot-board, Fig. 5. The foot-board is held to the racks by means of hooks d , pivoted at d' to

the ends of the foot-board and embracing the racks. These hooks permit the foot-board 35 to be tilted and moved along the rack, but not to be disengaged therefrom. Each hook is notched at its lower edge, as at d^2 , to engage a pin e , projecting laterally from the edge of the foot-board.

In use the foot-board, if to be adjusted, is tilted upon the teeth of the rack as a fulcrum. When its beveled inner edge c' has assumed a position parallel to the rack, the foot-board may be raised or lowered to the 40 desired extent. Then the foot-board is swung outward into a horizontal position, so that its plate c^2 rests upon and is supported by the teeth of racks b . Downward tilting of the foot-board will now be prevented by the pins 45 e , engaging the notches d^2 of hooks d , and thus the foot-board is in proper position to serve as a foot-rest.

What I claim is—

The combination of a chair with a pair of 55 bent racks b , secured to the chair-legs, a foot-board c , having beveled edge c' , supported upon the teeth of the rack, hooks d , pivoted to the ends of the board and embracing the racks, and with pins e , secured to the foot-board below the hooks, substantially as specified.

PETER WARD.
